W. S. GILKEY

LOOSE LEAF HOLDER

Filed Oct. 20. 1923

INVENTOR:

William S. Gilkey

BY *Oliver Ernestel*,
HIS ATTORNEY.

Patented July 8, 1924.

UNITED STATES PATENT OFFICE.

WILLIAM S. GILKEY, DECEASED; BY VIRGINIA K. GILKEY, OF CLEVELAND HEIGHTS, OHIO, AND THE GUARDIAN SAVINGS & TRUST COMPANY, OF CLEVELAND, OHIO, A CORPORATION OF OHIO, EXECUTORS, ASSIGNORS TO THE W. S. GILKEY PRINTING COMPANY, OF CLEVELAND, OHIO, A CORPORATION OF OHIO.

LOOSE-LEAF HOLDER.

Application filed October 20, 1923. Serial No. 669,864.

To all whom it may concern:

Be it known that the undersigned, VIRGINIA K. GILKEY, a citizen of the United States, and THE GUARDIAN SAVINGS & TRUST COMPANY, a corporation organized and existing under the laws of the State of Ohio, and having its principal office in Cleveland, county of Cuyahoga, and State of Ohio, joint executors of the estate of WILLIAM S. GILKEY, deceased, believe that the said

WILLIAM S. GILKEY invented new and useful Improvements in Loose-Leaf Holders, of which the following is a specification, the principle of the invention being herein explained and the best mode in which he contemplated applying that principle, so as to distinguish it from other inventions.

This invention relates to holders for loose-leaves, whereby said leaves may be readily and detachably secured to such holder and the latter act as a platen for use when the leaves are written upon.

The object of the invention is to provide a device of the above described character which is simple in, and hence economical of, construction and which may be easily and readily manipulated.

Said invention consists of means herein-after fully described and set forth in the claim.

In the annexed drawings:—

Figure 1 represents a plan of a device embodying the said invention.

Fig. 2 represents a fragmentary portion thereof upon an enlarged scale.

Fig. 3 represents a section taken upon the plane indicated by line III—III in Fig. 2.

In the illustrated embodiment of the invention, the platen member 1 consists of a rectangular wooden board from whose left-

hand marginal portion there projects upwardly two holding pins 2—2, so spaced that they will engage superposed perforations which are provided upon the left-hand mar-

ginal portion of the loose-leaves 3, as is customary in this class of loose-leaf forms and particularly in what is known as "car wheel report" forms used by railroads in keeping track of movements of freight cars.

Pivotal secured to this marginal portion of the board, by means of two rivets

4—4, are two clips 5—5. Each of these clips is made of spring steel and is normally convex intermediate of its ends as shown in Fig. 3. The outer or free end of each clip is provided with a laterally extending offset portion 6 which is pierced by an elongated slot 7. The width of this slot is such as will permit it to readily receive a pin 2. The rivets 4 are located some distance to the left of the edge of the forms 3 when the latter are secured in place by the pins as shown in Fig. 1, and the offset portion 6 is thereby permitted to extend over and press upon the loose-leaves while the main or body portion of the clips remains parallel with the edge of the forms.

The outer edge portion 8 of the free or swinging end of each clip is up-turned to form a lower curved surface 9 which bears upon the paper, and being so curved produces the necessary pressure without damaging the forms. This up-turned portion also provides a convenient grip for raising the clips so as to disengage the pins when it is desired to remove the forms or replace same.

To effect such removal, the clips are raised as shown in dotted lines in Fig. 3, and then swung upon their pivots as shown in dotted lines in Fig. 2, whereupon the loose-leaves may be disengaged from the pins as will be readily understood.

It will also be understood that the normal curvature of the clips, that is, its curvature when the clips are not in tension, is greater than the curvature thereof when the clips are in engagement with the sheets as shown in Fig. 3, thereby reducing the required pressure upon such sheets during such engagement.

What I claim is:

A loose leaf holder comprising a platen member adapted to receive superposed sheets thereon; pins upstanding from one marginal edge portion of the platen to engage through apertures in the sheets and hold the latter in position; and a spring clip for each pin, each clip comprising an elongated resilient arm pivoted at one end to the platen at the marginal edge portion thereof and extending along said portion

1,000,012

away from the edges of the sheets fitting over the pins, each clip having on its laterally offset portion arranged

overlap the superposed sheets and having an elongated slot to receive the adjacent pin therethrough, said free end and offset portion of each clip being adapted to be raised from the sheets and the clip being adapted to be swung about its pivot

away from the pin to free the sheets for removal and substitution.

Signed this 17th day of October, 1923.

VIRGINIA K. GILKEY,
[L. S.] THE GUARDIAN SAVINGS &
TRUST COMPANY,
By A. F. YOUNG, Vice-President,
Executors of William S. Gilkey, deceased.
